HEAT EXCHANGE DEVICE

Philmore F. Sperry, Chicago, Ill., assignor to
 Excel Auto Radiator Company, a corporation
 of Delaware

Application March 20, 1937, Serial No. 132,000

14 Claims. (Cl. 257—137)

The present invention relates in one of its uses to heat exchange apparatus and is particularly adapted to be embodied in a heater of the type commonly employed in automobiles to utilize the heat of the cooling fluid in the internal combustion engine to heat air which is thereafter used to heat the interior of the automobile and to clear the windshield.

Generally speaking the invention contemplates the provision of a composite fan structure by virtue of which an entire area is subject to efficient air and gas displacement through the agency of two appropriate fan elements which create two useful streams moving preferably toward opposite sides of a plane which is perpendicular to the axis of rotation of said fan elements, together with means to prevent any substantial commingling of said two streams at the fan structure. In view of the well known inefficiency of the central portion of a propulsion fan, my invention contemplates the addition of an efficient fan element so that the entire area of the fan structure creates an efficient air movement. The two fan elements are thus, in a sense, complementary. Even if the well known propulsion fan element were to extend completely toward the center of the complementary suction fan element the central portion of such propulsion fan blades would not seriously interfere with the air movement created by the suction fan.

One form of the invention is embodied in a heater comprising a housing which encloses a radiator core. An electric motor mounted on the housing drives an air circulating means which forces air through the radiator core in such a fashion as to effectively utilize all of the heating surfaces of the radiator core and to discharge air from the front side of the housing for heating the interior of the automobile while withdrawing air from the center of the radiator core with which to clear the windshield or for other purposes.

The radiator core comprises spaced headers connected by suitable pipes which lead to the circulation system for the cooling fluid of the internal combustion engine. The headers are connected by tubes and suitable radiating fins are mounted in spaced relation on the tubes. A motor drives a fan for forcing air across the tubes and between the heat radiating fins thereon. In the present device, means are provided whereby that part of the radiator core which is centrally disposed with respect to the fan is utilized to its fullest extent in heating air, by replacing the inefficient central portion of propulsion fan blades by an efficient fan structure.

The features and advantages of the invention will appear more readily from the following description, reference being had to the accompanying drawings wherein a preferred form of the invention is shown:

In the drawings—

Fig. 1 is a vertical sectional view through a heat exchange device embodying the invention; and

10 Fig. 2 is a section on the line 2—2 of Fig. 1. Referring now in detail to the drawings, the heat exchange device comprises a housing 5 having a plurality of shutters 6, 7, 8, and 9 across one face thereof. The shutters are pivoted in a ring 10 mounted in the housing by means of ears 11 mounted on the shutters and pivot pins 12. The ring 10 is held in position inside a flange 13 on the housing 5 by a plate 14 fastened to a stud 15 on the housing 5 by a screw 16 and by spring clips 17 fastened to studs 18 by screws 19 so that the ring 10 may be rotated. A handle 20 is provided on the ring for turning it into various positions of adjustment.

25 The housing 5 has a rest 21 for supporting a radiator core 22. The radiator core 22 comprises a lower header 23 and an upper header 24. The headers are connected by tubes 25. Spaced fins 26 are mounted on the tubes 25. The header 23 is connected to a pipe 27 and the header 24 is connected to a pipe 28. The pipes 27 and 28 are utilized to connect the radiator core into the circulating system for the cooling fluid of an automobile engine. A post 29 spaces the header 23 from the front of the housing 5 and a post 30 spaces the header 24 from the front of the housing.

35 A back plate 31 is mounted on the housing 5 by a plurality of screws 32. The back plate 31 has a central opening 33 and a flange 34 around the opening 33. A mounting bracket 35 is secured against the back plate by spot welding a pair of flanges 36 and 37 to the back plate. The back plate also carries a pair of fan supporting brackets 38 and 39 which are secured to the back plate by spot welding.

40 45 A motor 40 is supported on the brackets 38 and 39 by a mounting plate 41. The plate 41 is riveted or otherwise secured to the housing of the motor 40 and is fastened to the brackets 38 and 39 by bolts 42 and 43. A fan housing 44 is secured on the plate 41 by a plurality of rivets 45 and 46. The housing 44 has a small opening at 47 through which a shaft 48 of the motor projects into the housing 44. The shaft 48 has a fan unit 50 secured thereon by a hub 49. The hub

49 is welded or otherwise secured to the fan unit 50 and is fixed to the shaft 48 by a set screw 51.

The fan unit 50 comprises a cylindrical portion 52 provided with vanes 53 adapted to draw air out from the interior of the cylindrical portion and discharge it into the housing 44. The housing 44 is provided with an outlet 54 to which a flexible tube 55 may be applied for conducting the air from the housing 44 to any desired point, such for example as the windshield of the automobile. The cylindrical shell 52 of the fan unit 50 is open at its outer end and carries a ring 56 upon which a plurality of fan blades 57 are secured. The ring 56 is welded to a flange 58 on the shell 52 and the blades 57 are welded to the ring 56. A ring 59 is secured on the fins 26 of the radiator core and is preferably slightly larger than the interior diameter of the ring 58.

The core 22 is pressed against the stops 28 and 30 by the back plate 31 and suitable yielding pads 60 and 61 are interposed between the back plate 31 and the headers 23 and 24, respectively.

The operation of the device is as follows:

When the fan unit 50 is rotated, the fan blades 57 are so arranged as to force air from the back of the housing 5 through the radiator core and out past the shutters 6, 7, 8, and 9. The shutters 6, 7, 8, and 9 may, of course, be open to any desired degree. The fan vanes 53, however, will at the same time discharge air out into the housing 44 and draw air through the radiator core 22 and through the ring 59 into the interior of the shell 52. In this manner the central portion of the radiator core is utilized in heating air for discharge through the housing 44 to the flexible tube 55. The fan blades 57 drive air through the rest of the core and in this way utilize the core to its fullest advantage in deriving heat from the liquid circulating through the core to the air.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible in view of the prior art.

Having thus described my invention, what I claim as new and desire to secure by Letters Patent is:

1. In combination, a heat exchange device comprising a housing, a radiator core disposed within said housing, and means for circulating air through the radiator core, said means comprising a suction fan having an intake opening for withdrawing air from the central portion of said core and a radially outer fan driving air into the outer portions of said core.

2. In combination, a heat exchange device comprising a housing, a radiator core disposed within said housing, and means for circulating air through the radiator core, said means comprising a suction fan having an intake opening for withdrawing air from the central portion of said core and a radially outer fan driving air into the outer portions of said core and a fan housing for the inner fan having a discharge outlet for connection to an air conduit.

3. In combination, a heat exchange device comprising a housing, a radiator core disposed within said housing, and means for circulating air through the radiator core, said means comprising a suction fan having an intake opening for withdrawing air from the central portion of said core

and a radially outer fan driving air into the outer portions of said core, and a ring on said core adjacent the fans and providing a barrier around the inlet from the core to the inner fan.

5 4. In combination, a heat exchange device comprising a housing, a radiator core disposed within said housing, and means for circulating air through the radiator core, said means comprising a suction fan for withdrawing air from the central portion of said core and a radially outer fan driving air into the outer portions of said core, said inner suction fan comprising an annular shell having vanes in its periphery for removing air from the interior of the shell and having a central opening toward the core, and said outer fan comprising fan blades mounted on said shell near said central opening.

10 5. In combination, a heat exchange device comprising a housing, a radiator core disposed within said housing, and means for circulating air through the radiator core, said means comprising a suction fan for withdrawing air from the central portion of said core and a radially outer fan driving air into the outer portions of said core, said suction fan comprising an annular shell having vanes in its periphery for removing air from the interior of the shell and having an axial opening centrally of said core, and said outer fan comprising fan blades mounted on said shell outwardly of said axial opening, a housing for said shell, said housing having a peripheral discharge opening, said fan blades being outside the shell housing.

15 6. In combination, a heat exchange device comprising a radiator core having inlet and outlet means for connection to a source of heating fluid, and means for circulating air through said core, said means comprising fan means forcing air in one direction through the central portion of said core, and a second fan means forcing air in the opposite direction through that part of the core surrounding the central portion, said first named fan means comprising an annular shell having vanes in the periphery thereof, and said second fan means comprising fan blades carried by said shell.

20 7. In an automobile body heater, a substantially vertical forwardly facing radiator, a unitary fan member rotatably mounted about a substantially horizontal axis in back of said radiator, said unitary fan member including a centrifugal fan having a substantially circular extension thereon forming the centrifugal fan inlet, said unitary fan member also including blade members on said extending portion and extending radially outwardly beyond the outer periphery of said centrifugal fan, said blade members being positioned forwardly of said centrifugal fan, and a motor for driving said unitary fan member.

25 8. In an automobile body heater assembly, in combination, a radiator, an axial flow type of fan in back of said radiator for forcing air forwardly through said radiator, a centrifugal type of fan in back of said axial flow type of fan, means forming a conduit between said radiator and centrifugal fan passing centrally through said axial flow type of fan, and means for driving said fans.

30 9. As an article of manufacture, a fan unit comprising a substantially cylindrical portion having one of its ends substantially closed, longitudinally extending slots having vanes associated therewith in said cylindrical portion forming a centrifugal fan, the other end of said cylindrical member forming an inlet duct for said centrifugal fan, outwardly directed blade members secured to

said centrifugal fan about said inlet duct forming a propeller fan, and means to collect the discharge from said centrifugal fan separate from said propeller fan.

10. In combination, a heat exchange device comprising a radiator core, and means for circulating air through the radiator core, said means comprising a suction fan withdrawing air from the central portion of said core and a radially outer fan driving air into the outer portions of said core.

11. In combination, a heat exchange device comprising a radiator core having inlet and outlet means for connection to a source of heating fluid, and means for circulating air through said core, said means comprising fan means withdrawing air in one direction through the central portion of said core, and a second fan means forcing air in the opposite direction through that part of the core surrounding the central portion, said first named fan means comprising an annular shell having vanes in the periphery thereof and a central intake opening, and said second fan means comprising fan blades extending radially outwardly of said intake opening.

12. In combination, a heat exchange device, a

complementary fan structure rotatably mounted about a substantially longitudinal axis in juxtaposition to said device, said structure including a centrifugal suction fan comprising a shell including a portion defining a central intake opening and propulsion fan blades extending outwardly from said portion, and means to prevent substantial commingling of the streams created by the said two fans at the fan structure.

13. A fan structure comprising, a centrifugal suction fan having a central intake opening, a propulsion fan extending outwardly from said suction fan, a single motor for driving both fans, said propulsion fan consisting of blades sloped so as to create, when rotated, a stream flowing in a substantially opposite direction to the stream flowing into said suction fan, and means to collect the discharge from said centrifugal fan separate from said propulsion fan.

14. A fan structure comprising a centrifugal suction fan having a central intake opening, a propulsion fan extending outwardly from said opening, and a housing surrounding said suction fan with an outlet separate from the air stream of said propulsion fan.

PHILMORE F. SPERRY.
